Foxes & Harrison.

Fire Escape.

No 35,601.

Patented June 17, 1862.

UNITED STATES PATENT OFFICE.

DANIEL FOBES, OF BOSTON, AND HENRY M. HARTSHORN, OF MALDEN, MASSACHUSETTS.

IMPROVEMENT IN FIRE-LADDER APPARATUS.

Specification forming part of Letters Patent No. 35,601, dated June 17, 1862.

To all whom it may concern:

Be it known that we, DANIEL FOBES, of Boston, in the county of Suffolk, and HENRY M. HARTSHORN, of Malden, in the county of Middlesex, and State of Massachusetts, have invented an Improved Fire-Ladder Apparatus; and we do hereby declare that the same is fully described and represented in the following specification and the accompanying drawings, of which—

Figure 1 is a side elevation, Fig. 2 a front elevation, and Fig. 3 a longitudinal section, of it. Fig. 4 is a top view, and Fig. 5 a rear elevation, of the window-breaker and its stream-pipe operating devices. Fig. 6 is a rear elevation of the shafts, gears, and windlasses by which the window-breaker and its stream-pipe lines are operated. Figs. 7 and 8 are vertical and longitudinal sections of such shafts and the mechanism applied to them. Fig. 9 is an end view of one of the reversible pulleys, to be hereinafter described. Fig. 10 is a side view, and Fig. 11 an edge view, of a ladder-section used for making extension of the movable main section C of the ladder. Fig. 12 exhibits the mode of applying the auxiliary ladder-section D to the main ladder-section C.

In such drawings, A represents a frame or carriage, supported by four wheels, a a b b, and having a perch or tongue, c, to extend over and rest upon the axle d of the front wheels, the same being so as to enable the front wheels to be turned about horizontally, as in ordinary four-wheeled carriages. The said frame A supports a ladder, B, so applied to the two upper corners of the frame, or to the frame in the vicinity thereof, as to be capable of being turned and elevated from a horizontal or nearly horizontal position into either a vertical or such an inclined position as circumstances may require. A portion of the said ladder B extends below its fulcrum-rod E, as shown in the drawings, and has two ropes, f f, applied to it at or near its lower ends, and made to extend from it backward and underneath a guide-roller, g, and to a windlass, h, arranged within the carriage A, as shown in the drawings. The said windlass h carries a ratchet, i, with which a spring-retaining click, k, supported by the frame A, operates. By means of such windlass and its ropes the

ladder B may be turned on its fulcrum and raised on its carriage into either a vertical or an inclined position.

A second ladder, C, is placed within the main ladder B, and is supported by it, so as to be capable of being slid or moved longitudinally relatively to it, projecting or flange-plates i' i' serving to maintain the ladder C against the rounds of the ladder B. The lower round of the said ladder C carries a recessed toothed shoulder, k', and, furthermore, the foot of each of the bars of the said ladder C is furnished with a socketed piece, m, for the reception of a tenon, n, of the third or extension ladder, (exhibited at D in Figs. 10 and 11,) this latter ladder also being constructed with forked braces o o and with a toothed shoulder, k', applied to it, as shown in the drawings. Furthermore, in order to sustain the fire-ladder apparatus laterally, it may have shores or struts E' E', which may be hinged or jointed to the upper part of the main ladder B, and made to project therefrom and rest upon the ground when the apparatus is in use.

In order to effect the raising of the ladder C within and relatively to the ladder B, we apply to the said ladder B an endless chain or belt, F, working around a toothed wheel, G, and a guide-roller, H, arranged as shown in the drawings, the wheel G being carried by a cranked shaft, I. Furthermore, a lifter-tooth, L, is applied to and projects from the endless belt in such manner that while the latter may be in movement, caused by the rotation of the wheel G, such lifter may be received into the recessed shoulder k', and by pressure against the same cause the ladder C to be slid upward within the ladder B. When the said ladder C has attained the highest point of elevation capable of being imparted to it by the endless belt and the lifter, the latter will pass or be drawn out of the recess of the shoulder k' and the ladder C, and will be caught and retained in position by a spring-pawl, p, affixed to the ladder B, and made to enter a notch, q, properly formed in the rear side of one of the bars of said ladder C, such notch being exhibited in Fig. 1 by dotted lines.

In case it should be desirable to produce a further upward elevation of the ladder C, the third ladder, D, is to be first applied to it

and within the ladder B. In making this application the tenons $n\ n$ of the ladder D are to be inserted within the recessed parts $m\ m$, and so as to cause the forked bars $o\ o$ to receive into their notches and to straddle the lower round or foot-bar of the ladder C. This having been accomplished, the lifter-tooth L, after having passed downward toward and around the toothed wheel G, will be caused to enter the recessed shoulder k^2 of the third ladder, D, and by pressure against the same will raise it and the second ladder, C, simultaneously until such lifter-tooth L shall be raised up to the roller H, when it will pass out of the said part k^3 , and the ladder D will be caught and retained by the spring-pawl p taking into a notch, q, formed in said ladder, as shown in Fig. 41. This third ladder, D, may also be supplied at its foot with socket-pieces, by which another such ladder may be applied to it. Thus any number of such ladders may be joined to one another and with the ladder C, so as to enable it to be projected to any desirable height.

We apply to the ladder C a hooked frame or window-breaker, L', formed as shown in the drawings, it being hinged to the ladder so as to be capable of being moved in a vertical direction, so as to fall against and break through a window when circumstances may require it to be employed for such purpose. In this case the hooks $r\ r$ of the window-breaker will pierce the panes and break down the sashes of such window, and by catching on the sill will hold the upper part of the said ladder apparatus hooked to a building when on fire. Two ropes or chains, $s\ t$, are attached to the said window-breaker, one of them being led therefrom toward and through the upper part of the ladder C, and thence down to one of two windlasses, $u\ v$, placed upon a horizontal shaft, M, the same being arranged as shown in the drawings. The outer rope or chain, t , is led downward and attached to the other windlass. This latter windlass is fastened firmly to the shaft M, so as to be movable therewith. Furthermore, the shaft M has another shaft, N, underneath it, both shafts being supported by the frame A. On this latter shaft are placed four other windlasses, $w\ x\ y\ z$, so applied to it as to be capable of freely rotating thereon. The two shafts M and N are connected by gears $a'\ b'$, so that one may be revolved by means of the other.

We would remark that each of the windlasses v , w , and z is what we term a "reversible" windlass or pulley, it being so applied to its shaft as to be capable of being drawn endwise off the same and reversed or turned end for end, and so replaced on the shaft. There is a notched projection, c' , applied to each end of the windlass or pulley v , it being so constructed as to enable a key, d' , to pass through it and the shaft for the purpose of locking the windlass pulley v to the shaft. Furthermore, there is such a notched projection c' and key d' applied to the shaft N and

each of its outermost windlasses or pulleys, w , z , the inner end of each of said pulleys being formed with a square tenon, f' , to enter a corresponding recess, g' , formed in the adjacent end of the adjacent windlass, x or y , which is furnished with handles $h'\ h'$, radiating from one of its heads, as shown in the drawings, and particularly in Fig. 13, which is an end view of the said windlass.

The window-breaker L carries a horizontal rocker shaft or frame, O, which turns in a vertical plane, and is slotted or formed with a recess, h^2 , to enable a stream-pipe, i^2 , to extend through and turn horizontally in it. Two arms, $k'\ k'$, extend at right angles to and in opposite directions from the frame O, as shown in the drawings. From these arms two chains or ropes, $l'\ m'$, extend. Furthermore, there are two other chains or ropes, $n'\ o'$, which are affixed to the front part of the stream-pipe i^2 , and pass through the recess h' and against pulleys or guides $p'\ p'$.

All four ropes or chains, $l'\ m'\ n'\ o'$, are led forward through the ladder C, and thence downward. A hose, P, proceeds from the stream-pipe backward through the ladder C, and thence downward, as shown in the drawings. By means of the four ropes or chains $l'\ m'\ n'\ o'$ the stream-pipe may be turned so as to point either to the right or left, or upward or downward, as circumstances may require.

The windlasses $u\ v$ afford the means of working the ropes or chains by which the window-breaker can be elevated or depressed, in which case they are to run in opposite directions around the said windlass. With respect to the windlasses $w\ x\ y\ z$, they are for operating the ropes or chains $l'\ m'\ n'\ o'$, which lead, respectively, to such windlasses, two ropes being carried to one pair, while the other two ropes are led to the other pair of them. While arranged for working the stream-pipe each set of its ropes or chains winds in opposite directions about its two windlasses—that is, while one rope winds in one direction about its windlass, the other is wound in an opposite direction about the other windlass, and thus, by turning the two windlasses in either direction, one rope will wind on one windlass and the other rope unwind from the other windlass. Consequently, by means of the two sets of handles of the windlasses, an individual will be enabled to impart any desirable direction to the stream-pipe—that is, he can move it either up or down or sidewise, either to the right or left, and thus direct a stream of water from it into any part of a building, into a window of which the pipe may enter. It should be mentioned, however, that under such circumstances each pair of windlasses $w\ x$ or $y\ z$ will be locked together and free to revolve on their shaft N without turning it. Now, if each reversible windlass or pulley be removed from its shaft and next turned around and again applied to the shaft, so as to bring next to its fellow windlass that face or side of the pulley which before was farthest from it, we shall have the

lines of all the windlasses leading around them in one direction. On the shaft-keys being restored to their places it will be found that the windlasses will be so locked to their shafts M N that when the lower shaft is put in revolution by power applied to its windlass-handles the other shaft will be revolved. Under these circumstances all the ropes or chains of the six windlasses may be either wound up or let out simultaneously as the auxiliary ladder or ladders are being either raised or lowered.

We do not claim the application of a supporting-platform to the upper part of an extension-ladder; nor do we claim the combination and arrangement of a water-conduit or hose-pipe director and guiding-lines with an extension-ladder, as shown in the patent of Joel Moulton.

We claim—

1. The combination of mechanism employed in elevating the ladder-sections, the same consisting of the endless chain or band F, the lifter-tooth L, the pawl *p*, the tooth-shoulder *k*, and the pawl-notch *q*, or mechanical equivalent, applied to the main ladder and each section, and operating therewith substantially as specified.

2. The combination of the movable hooked window-breaker L and its operating lines or chains with the extension-ladder, the same being to operate in manner and for the purpose with respect to such ladder as specified.

DANIEL FOBES.

HENRY M. HARTSHORN.
